Design, Dec. 1962, p. 71, Hair dryer at bottom right.

Primary Examiner—Louis S. Zarfas

Attorney, Agent, or Firm—Richard A. Wise

[57] CLAIM

The ornamental design for a hair dryer, as shown and described.

DESCRIPTION

FIG. 1 is a front elevational view of a hair dryer showing my new design;

FIG. 2 is a left side elevational view thereof;

FIG. 3 is a top plan view thereof;

FIG. 4 is a right side elevational view thereof;

FIG. 5 is a back elevational view thereof; and

FIG. 6 is a bottom plan view thereof.

The cord is depicted only partially for convenience of illustration.
